UNITED STATES PATENT OFFICE

2,463,160

SHOE SUPPORTING FORM

Milton L. Dodge, Newburyport, Mass., assignor
to Compo Shoe Machinery Corporation, Bos-
ton, Mass., a corporation of Delaware

Application June 14, 1944, Serial No. 540,209

9 Claims. (Cl. 12—128.5)

1

This invention relates to forms for supporting shoes and more particularly while their uppers are being shaped and smoothed, and has for an object to provide a form arranged to support shoes of different sizes and presenting a smooth surface to the inside of the shoe and against which the shoe upper may be pressed.

For a complete understanding of this invention, reference may be had to the accompanying drawings in which

Figures 1 and 2 are side and top plan views, respectively, of a form for supporting a shoe, the position of a shoe supported thereon being shown in broken lines in Figure 1.

Figure 3 is a detail sectional view on line 3—3 of Figure 1.

Referring first to Figures 1, 2 and 3, a shoe supporting form 1 is shown comprising a central section 2 of the general shape of the rear portion of a last and including the upper portion of the last against which the top edge of the shoe upper may engage. This section 2 terminates short of the sole face of the form which is composed of a pair of sections 3 and 4. Each of the sections 3 and 4 is pivoted to the section 2 adjacent to its rear end as on the pivot screws 5, so that by separating the forward ends of the sections 3 and 4, the sides of the form may be expanded and by pushing them toward each other they may be contracted. Forms 1 may be made in rights and lefts.

In order to present a smooth surface to the inside of a shoe placed on the form and for other purposes, as will later appear, a sheet material cover 10 encloses the sections 2, 3 and 4. This sheet cover, which is preferably but not necessarily copper or other metal of good heat conductivity, has its top edges inwardly turned as at 12 to overlie the sole faces of the pair of sections 3 and 4 and to these faces these overlying portions are secured toward the rear ends of the sections 3 and 4 as by screws 15. Opposite edges of the cover 10 which overlie the side faces of the section 1 have attached thereto electric heating elements 20, these elements being attached to the inner face portions of the sheet metal cover 10 on the inside and being received in recesses 21 in the section 1 adjacent to its edge. The sheet metal casing 10 is also secured centrally adjacent to its rear end to the exposed face of the section 2 as by a screw 23. The central section 2 is also provided with a jack pin hole 25 so that the form may be mounted sole-side up on any suitable form or jack to present a shoe placed thereover with its sole face uppermost.

The forward portions of the sections 3 and 4 may be forced apart, thus to expand the form, the casing 10 being free to conform generally thereto, and more particularly when the upper of a shoe supported on the form is pressed thereagainst, being unattached thereto forwardly of

2

the screws 15 and 23, and for this purpose the confronting faces of the sections 3 and 4 are recessed as at 26, the rear face of the recess being beveled rearwardly as shown at 27 in Figure 1. Against this beveled face and between the sections 3 and 4 may be positioned a conical point 28 of an expanding screw 29 which extends upwardly and rearwardly through a threaded hole 30 in the section 2. This screw 29 may be provided with a threaded socket 31 in its outer end for the reception of a threaded element 32 of a handle 33. This handle 33 is preferably made of some heat insulating composition, such as one of the synthetic resins, so that it may be turned by the fingers of the operator as desired without becoming uncomfortably hot from the effect of the electric heaters 20. By turning the screw 29 inwardly so that its point 28 is pressed against the adjacent edges of the walls 27, the sections 3 and 4 may be forced apart at their forward ends. By relaxing this screw, these forward ends are pulled together as by a coil spring 35 engaged at opposite ends with pins 36 as secured in the sections 3 and 4 and projecting into recesses 37 therein within which the spring ends are engaged therewith.

The sheet metal covering 10 provides a smooth exterior surface for engagement with the inside of the shoe upper placed over the form and bridges across the junctures between the elements 2, 3 and 4, regardless of the widthwise adjustment of the sections 3 and 4. As shown, also, this metal cover extends substantially throughout the shank portion of the form so as to engage throughout substantially the entire heel end and shank portion of a shoe placed thereover. By reason of the heating of this metal cover, the entire inner face of the shoe throughout the heel end and preferably also substantially throughout the shank portion, is subjected to heat which thus shrinks the lining and as the shoe upper is pressed thereagainst, as will later appear, irons out any wrinkles which may be present therein when the shoe upper is treated. The expansion and contraction widthwise of the form makes it possible to treat shoes of considerable variation in size and width on the one form.

This supporting form as shown is particularly well suited for supporting shoes in connection with mechanism for pressing the shoe uppers shown in my application Serial No. 600,924 filed June 22, 1945, as a division of this application, for Shoe upper shaping and smoothing machines which has matured into Patent No. 2,433,266, granted December 23, 1947, before "as a division."

From the foregoing description of an embodiment of this invention, it will be understood by those skilled in the art that various changes and modifications might be made without departing from the spirit or scope of this invention.

I claim:

1. A shoe form comprising longitudinally extending relatively movable sections, means securing said sections together with capability of lateral expansion or contraction, and a sheet metal cover for said form secured to certain of said sections and presenting a substantially continuous surface for engagement with the inner face of the upper of a shoe placed on said form substantially throughout the back and sides of the heel portion of such shoe.

2. A shoe form comprising longitudinally extending relatively movable sections, means securing said sections together with capability of lateral expansion or contraction, and a sheet material cover for said form secured to certain of said sections and presenting a substantially continuous surface for engagement with the inner face of the upper of a shoe placed on said form substantially throughout the back and sides of the heel and shank portions of such shoe.

3. A shoe form comprising longitudinally extending relatively movable sections, means securing said sections together with capability of lateral expansion or contraction, a sheet metal cover for said form secured to certain of said sections and presenting a substantially continuous surface for engagement with the inner face of the upper of a shoe placed on said form substantially throughout the back and sides of the heel portion of such shoe, and a heater for said cover.

4. A shoe form comprising longitudinally extending relatively movable sections, means securing said sections together with capability of lateral expansion or contraction, a sheet metal cover for said form secured to certain of said sections and presenting a substantially continuous surface for engagement with the inner face of the upper of a shoe placed on said form substantially throughout the back and sides of the heel portion of such shoe, certain of said sections being recessed, and an electric heater within said recess secured to said cover.

5. A shoe form comprising a central section shaped to the top portion of a last and terminating short of the sole face, a pair of longitudinal sections each having a lengthwise portion of the last sole face and a portion of the last side face, said longitudinal sections being pivoted adjacent to their heel ends to the bottom face of said central section to move across the bottom face of said central section and together with said central section presenting surfaces constituting the major portion of a substantially continuous shoe supporting member for the heel and shank of a shoe, and means for angularly adjusting the sections of said pair.

6. A shoe form comprising a central section shaped to the top portion of a last and terminating short of the sole face, a pair of longitudinal sections each having a lengthwise portion of the last sole face and a portion of the last side face pivoted adjacent to their heel ends to the bottom face of said central section and together with said central section presenting surfaces constituting the major portion of a substantially continuous shoe supporting member for the heel and shank of a shoe, means for angularly adjusting the sections of said pair, and a continuous sheet material cover for said form having edge portions overlying and secured to the sole faces of said pair of sections and to the top face of said central section adjacent to the heel end of said form.

7. A shoe form comprising a central section shaped to the top portion of a last and terminating short of the sole face, a pair of longitudinal sections each having a lengthwise portion of the last sole face and a portion of the last side face pivoted adjacent to their heel ends to the bottom face of said central section and together with said central section presenting surfaces constituting the major portion of a substantially continuous shoe supporting member for the heel and shank of a shoe, means for angularly adjusting the sections of said pair, and a continuous sheet material cover for said form having edge portions overlying and secured to the sole faces of said pair of sections and to the top face of said central section adjacent to the heel end of said form, said cover extending forwardly substantially through the shank portion of said form and free from attachment to said sections at its forward portion.

8. A shoe form comprising a central section shaped to the top portion of a last and terminating short of the sole face, a pair of longitudinal sections each having a lengthwise portion of the last sole face and a portion of the last side face pivoted adjacent to their heel ends to the bottom face of said central section and together with said central section presenting surfaces constituting the major portion of a substantially continuous shoe supporting member for the heel and shank of a shoe, means for angularly adjusting the sections of said pair, a continuous sheet metal cover for said form having edge portions overlying and secured to the sole faces of said pair of sections and to the top face of said central section adjacent to the heel end of said form, and an electric heating element secured to said cover.

9. A shoe form having lengthwise sections extending substantially to the heel end of the form and relatively movable from and toward each other, and a cover for said form presenting a continuous surface about the heel end of the form bridging said sections for contact with the inside face of a shoe placed over said form.
